UNITED STATES PATENT OFFICE.

SIMON E. PEARSON AND BERNARD D. GORMAN, OF GENOA, NEBRASKA.

DESIGN FOR A TYPE-WRITER TABLE.

42,296.

Specification for Design. Patented Mar. 12, 1912.

Application filed November 8, 1911. Serial No. 659,254. Term of patent 7 years.

To all whom it may concern:

Be it known that we, SIMON E. PEARSON and BERNARD D. GORMAN, citizens of the United States, residing at Genoa, in the county of Nance and State of Nebraska, have invented a certain new, original, and ornamental Design for a Type-Writer Table, of which the following is a specification, reference being had therein to the accompanying drawing:

The figure is a perspective view of a type-writer table, showing the new design.

We claim:

The ornamental design for a typewriter table, as shown.

In testimony whereof we hereunto affix our signatures in presence of two witnesses.

SIMON E. PEARSON.
BERNARD D. GORMAN.

Witnesses:

M. I. PUGSLEY,
F. F. JOHNSON.
